UNITED STATES PATENT OFFICE.

CHARLES T. JONES, OF NEW YORK, N. Y.

DESIGN FOR A BUTTON-HOOK.

SPECIFICATION forming part of Design No. 11,876, dated July 20, 1880.

Application filed June 23, 1880. Term of patent 3½ years.

To all whom it may concern:

Be it known that I, CHARLES T. JONES, a citizen of the United States, residing at New York, in the county and State of New York, have invented and produced a new and original Design for Button-Hooks, of which the following is a specification, reference being had to the accompanying drawing, forming part thereof.

10 The figure represents a side view of my newly-designed button-hook, this view only being deemed necessary to fully illustrate my design.

15 The device is constructed of a single piece of wire in the form shown, the projecting ring *a* and intermediate twisted shank or neck *b* constituting the handle, and the extended and gradually-tapering loop the operative part. To the ring *a* is connected a representation

of a miniature glove, which may be stamped or embossed upon its surface, the whole forming 20 an attractive and suggestive symbol.

The representation of the glove may form a rigid part of the hook, if desired, or be made separate and suspended thereto by any suitable means. Therefore,

25 I claim—

The design for a button-hook herein shown and described, the same consisting of the tapering loop forming the outline of the operative part, the projecting ring *a*, and connected 30 glove symbol.

CHARLES T. JONES.
